UNITED STATES PATENT OFFICE.

FREDERICK W. PREYER, OF CANTON, OHIO, ASSIGNOR TO THE GIBBS MANUFACTURING COMPANY, OF CANTON, OHIO, A CORPORATION OF OHIO.

EMBROIDERY-HOOP.

1,244,892.

Specification of Letters Patent. Patented Oct. 30, 1917.

Application filed March 22, 1916. Serial No. 85,943.

To all whom it may concern:

Be it known that I, FREDERICK W. PREYER, a citizen of the United States, residing at Canton, in the county of Stark and State of 5 Ohio, have invented a new and useful Improvement in Embroidery-Hoops, of which the following is a specification.

The invention relates to a hoop composed of two rings, one adapted to telescope out- 10 side the other to hold a piece of fabric taut over the inner ring, for the purpose of em- broiding the fabric.

Many advantages attend the use of wooden 15 rings for this purpose, and a preferred method of increasing the resilience and friction of the holding surface of the inner ring is to attach or secure a resilient frictional band of felt or the like around the middle portion of its periphery.

20 When such a band is used, the best results are attained by transversely convexing the surface of the hoop underneath the band, and providing countersunk grooves for the edges of the band, so that the body of the 25 band will protrude, more or less positively, beyond the periphery of the rims of the ring; and difficulty has been experienced in retaining the inwardly deflected edges of the band within such countersunk grooves, 30 even though they may be glued therein, by reason of the rubbing and pulling action of the outer hoop and fabric upon the bands in the use of the hoop.

This difficulty has been overcome by pro- 35 viding U-shaped grooves, in the periphery of the ring adjacent to its edges, for receiving the edge portions of the band, so that the rim portion of the ring will overlap and thereby shield and secure the edges of the 40 band from being raised or detached from the ring.

The invention, thus set forth in general terms, is illustrated in the accompanying drawings, forming part hereof, in which— 45 Figure 1 is a perspective view of the inner ring of an embroidery hoop, showing the method of applying the frictional band in accordance with the present invention;

Fig. 2, a section of an embroidery hoop 50 with the fabric held therein, showing one method of embodying the present invention by the use of U-shaped grooves extending directly inward from the holding face of the inner ring;

55 Fig. 3, a similar view showing another

method of embodying the invention by the use of inclined U-shaped grooves diverging laterally under the rim portions of the ring; and

Fig. 4, shows a tool by which the band 60 can be readily mounted upon the ring, by inserting its edge portions in the U-shaped grooves of the ring and pressing the body of the band smoothly against its seat on the periphery of the ring. 65

Similar numerals refer to similar parts throughout the drawings.

The inner ring 1 or 1^a is made of wood, 70 hard rubber or other relatively hard material, and is formed with the annular U-shaped grooves 2 or 2^a countersunk in its periphery, adjacent to the edges thereof. These grooves may be countersunk directly inward as shown at 2 in Fig. 2, or may be countersunk in an inclined inward direction, as shown in Fig. 3; but in either case the depth of the grooves is deflected inward from the face of the ring. 75

The middle portion 3 of the periphery of 80 the ring, between the grooves, may be formed substantially flat or cylindric as shown in Fig. 2, so that when the band 4 is glued or otherwise attached thereon, the flat surface 5 is presented to the inner face of the outer ring 6, or to the interposed fabric 7; or 85 the middle portion 3^a of the periphery of the ring, between the grooves, may be curved or convexed in cross section, as shown in Fig. 3, so as to present a correspondingly curved or convex surface 5^a to the outer ring 90 6 or the interposed fabric 7.

In either case the formation of the U-shaped groove 2 or 2^a shapes the rim portions 8 or 8^a of the ring so that they will completely surround and overlap the edge 95 portions 9 and 9^a of the bands, when the same are inserted in the grooves, as shown more particularly in Figs. 2 and 3 of the drawings, thus shielding them from the abrading action of the outer ring or the pulling action of the fabric, and preventing the same from pulling or tearing the edge portions of the band from the inner ring. 100

It will be understood that the band is 105 mounted around the inner ring by inserting the edges of the band into the U-shaped grooves formed in the periphery of the ring, which may be done by the use of the tool 10 as shown in Fig. 1, or in any other con- 110

venient manner. It is also preferred to positively secure the band to the ring by means of glue or other adhesive material; and when so mounted and secured the overlapping of the rim portions of the ring around and upon the edge portions of the band protects the same from any rubbing or pulling action or contact which will tend to loosen or detach them from the ring.

10 I claim:

An embroidery hoop comprising two

rings one adapted to telescope within the other, one of the rings having U-shaped annular grooves countersunk in its holding face adjacent to the edges thereof, the depth 15 of said grooves being deflected inward from the face of the ring, and a resilient frictional band attached to the same face of the ring between the grooves and having its edged portions inserted in the grooves and 20 overlapped by the rim portions of the ring.

FREDERICK W. PREYER.
